US0D1052777S

(12) **United States Design Patent** (10) **Patent No.:** **US D1,052,777 S**
(45) **Date of Patent:** **** Nov. 26, 2024**

(54) **LIGHT FIXTURE**

(71) Applicant: **ABL IP Holding LLC**, Atlanta, GA (US)

(72) Inventors: **Luke Siefker**, Atlanta, GA (US); **Eric Chang**, Buford, GA (US); **Lucas Van Dyke**, Johns Creek, GA (US); **Jon Eric Gibson**, Covington, GA (US); **William E. Budzilene**, Monroe, GA (US)

(73) Assignee: **ABL IP Holding LLC**, Atlanta, GA (US)

(**) Term: **15 Years**

(21) Appl. No.: **29/765,494**

(22) Filed: **Jan. 8, 2021**

(51) LOC (14) Cl. **26-05**

(52) U.S. Cl.

USPC **D26/71; D26/92**

(57) **CLAIM**

The ornamental design for a light fixture, as shown and described.

DESCRIPTION

FIG. 1 is a top front isometric view of the light fixture.

FIG. 2 is a bottom rear isometric view of the light fixture of FIG. 1.

FIG. 3 is a front elevation view of the light fixture of FIG. 1.

FIG. 4 is a rear elevation view of the light fixture of FIG. 1. FIG. 5 is a side elevation view of the light fixture of FIG. 1. FIG. 6 is another side elevation view of the light fixture of FIG. 1.

FIG. 7 is a top plan view of the light fixture of FIG. 1; and, FIG. 8 is a bottom plan view of the light fixture of FIG. 1. The dash-dash broken lines illustrate portions of the light fixture. The dot-dash broken lines represent the bounds of the claim. The broken lines in the drawings form no part of the claimed design.

1 Claim, 8 Drawing Sheets
